UNITED STATES PATENT OFFICE.

EDWARD H. BUCKLEY AND JOSEPH L. DURKIN, OF PHILADELPHIA, PENNSYLVANIA.

PRINTING DEVICE.

Application filed August 29, 1923. Serial No. 659,884.

To all whom it may concern:

Be it known that we, EDWARD H. BUCKLEY and JOSEPH L. DURKIN, citizens of the United States, residing at Philadelphia, county of Philadelphia, and State of Pennsylvania, have invented certain new and useful Improvements in Printing Devices, of which the following is a specification.

Our invention relates to printing devices which are particularly adapted for printing the name of the bank on which a check is to be drawn.

The objects are to provide a printing device which will indelibly print the name of a bank on a check; will be selective to print the name of any desired bank; will do away with rubber stamps and pads, and be of simple and durable construction.

These objects, and other advantageous ends which will be described hereinafter, we attain in the following manner, reference being had to the accompanying drawings in which—

Figure 1 is a central section through a printing device constructed in accordance with our invention,

Figure 2 is a plan view of the device shown in Figure 1,

Figure 3 a section on line 3—3 of Figure 2,

Figure 4 a side view of the device shown in Figure 1,

Figure 5 a section on line 5—5 of Figure 3, illustrating the parts moved into another position,

Figure 6 a section on line 6—6 of Figure 3, the parts being moved into a printing position,

Figure 7 an enlarged section of the resilient connection between the crank and pivot,

Figure 8 an enlarged view, partly in section, of the telescoping arm which forms a part of my invention, and

Figure 9 an enlarged side view, partly in section, of a selecting knob.

Referring to the drawings, 1 indicates a base provided with two pairs of vertical guides 2. A block 3 is slidable between each pair of guides and rests on a spring 4 held in position between the guides by any suitable means. A rotor 5, fixed to a rotor shaft 6 rotatably mounted in blocks 3, is provided on its periphery with a series of faces 7 having their sides 8 undercut. Stamping dies 9, having impressions of the names of banks thereon, are provided with gripping springs

10 which engage undercut sides 8 and hold the dies to faces 7.

A selecting knob 11 has a shank 12 provided with an irregular end 13 which fits within a corresponding socket 14 in rotor shaft 6. The knob may be of any shape, but is preferably an octagon as shown in dot-and-dash lines in Figure 4, and may have names thereon corresponding with the names on the dies so that any desired die may be selected by merely turning the knob. Any type of indicator may be provided to indicate when the selected die is in proper position for printing. The names on the knob are preferably removable so that when a die is changed the name may also be changed.

The rotor is held in position for the selected die to do the printing by plungers 15 75 slidable in openings 16 in blocks 3 against the action of springs 17 and adapted to take into depression 18 at opposite sides of the rotor.

The rotor and selected die may be moved 80 downwardly, against the action of coiled springs 4 by presser arms 10, at opposite sides of the rotor, fixed to a shaft 20, rotatable in the base, and a lever 21 fixed to the shaft. When swung downwardly the presser arms engage blocks 3 and force the rotor downward. A torsion spring 22, having one end attached to the base and the other end attached to shaft 20, serves to return the presser arms to their idle position.

A link 23 pivotally connects each presser arm 19 with a crank 24 which is pivotally connected with a pivot 25 rotatable in the base, and resiliently connected therewith by a spring 26. An arm 27, fixed to pivot 25, 95 has a stem 28, with a collar 29 on its free end, which telescopes in a tubular part 30. A spring 31, embracing stem 28 is positioned between the collar and a cap 32 on the upper end of tubular part 30. The lower end of the tubular part provides a bearing for a roller shaft 33 which extends through roller guides 34 at opposite sides of the base. Guiding rollers 35, mounted on shaft 33, ride in guides 34 to guide an inking roller 36, fixed to shaft 33, across the face of the selected die. The inking roller 36 is normally in engagement with an ink-feeding pad 37 which is saturated with ink 38 from a well 39 in the base. A cap 40 covers an 110 opening 41 used for filling the well.

To use our improved printing device, the

rotor is turned by the selecting knob 11 so that the die with the name of the desired bank thereon is in position for printing. The check is inserted within the undercut opening 42 and lever 21 moved downward. During this movement presser arms 19, being operatively connected with inking roller 36, will move the inking roller from the position shown in Figure 1 across the face 10 of the die to the position shown in Figure 5 and apply a coating of ink to the selected die. After the roller has moved from the position shown in Figure 1 to the position shown in Figure 5, presser arms 19 will engage blocks 3. Further movement of lever 21 will move blocks 3 downward and rotor 5, being supported by the blocks, will move with the blocks until the selected die engages the check and prints the name of the bank 20 thereon. During this movement of lever 21, inking roller 36 will move from the position shown in Figure 5 to the position shown in Figure 6 and movement of the inking roller 36 and the parts connected therewith, 25 including pivots 25, will be stopped. Cranks 24, being freely mounted on pivots 25, will move with presser arms 19 and produce tension on springs 26. Upon releasing lever 21 torsion spring 22 will return it to 30 its normal position. During this movement presser arms 19 will move upward to release blocks 3 and permit coiled springs 4 to raise the blocks with the rotor and die. When the die is raised to its normal position, the tension on springs 26 is released, presser arms 19 will leave blocks 3 and return inking roller 36 to its normal position as shown in 35 Figure 1.

To change the dies on the rotor it is 40 merely necessary to rotate the rotor until the die to be changed appears in front of an opening 43. The die is then pulled through the opening by gripping a lip 44 and another die inserted through the opening and slipped onto the rotor.

While we have described our invention as taking a particular form, it will be understood that the various parts may be changed without departing from the spirit thereof, 50 and hence we do not limit ourselves to the precise construction set forth, but consider that we are at liberty to make such changes and alterations as fairly come within the scope of the appended claims.

Having thus described our invention, what we claim as new and desire to secure by Letters Patent is:—

1. A printing device including a base; printing dies; a rotor holding the dies, 60 adapted by rotation to position a selected die, and movable at an angle to its axis; means for inking the selected die, presser arms for moving the rotor, and connections between the presser arms and inking means 65 whereby initial movement of the presser

arms will actuate the inking means and ink the selected die and further movement of the presser arms will bring the inked die into contact with the slip to be printed.

2. A printing device including a base; 70 printing dies; a rotor holding the dies, adapted by rotation to position a selected die, and movable at an angle to its axis; means for inking the selected die; a lever combined with presser arms for moving the 75 rotor, and connections between the presser arms and inking means whereby part movement of the lever will actuate the inking means and ink the selected die and further movement of the lever will bring the inked die into contact with the slip to be printed, and means for returning the rotor and inking means to their idle position.

3. A printing device including a base having guides; blocks slidable in the guides; printing dies; a rotor, holding the dies, mounted in the blocks and adapted by rotation to position a selected die; means for inking the selected die, means including 90 presser arms for sliding the blocks and connections between the presser arms and inking means whereby the inking means will be actuated to ink the selected die before the blocks are slid to bring the inked die into contact with the slip to be printed.

4. A printing device including a base having guides; blocks slidable in the guides; printing dies; a rotor holding the dies, mounted in the blocks and adapted by rotation to position a selected die; means for inking the selected die; presser arms engaging with the blocks and fixed to a shaft 100 mounted in the base; a lever fixed to the shaft, and connections between the inking means and the presser arms whereby the initial movement of the lever will actuate the inking means and further movement will move the rotor to bring the selected die into contact with the slip to be printed.

5. A printing device including a base, 110 printing dies; a rotor holding the dies, adapted by rotation to position a selected die, and slidable in the base; a roller for inking the selected die; arms connected with the roller and pivoted to the base; means 115 for moving the arms to cause the inking roller to traverse the selected die, and means for sliding the rotor to bring the selected die into contact with the slip to be printed.

6. A printing device including a base, 120 printing dies; a rotor holding the dies, adapted by rotation to position a selected die, and slidable in the base; a roller for inking the selected die; telescoping arms connected with the roller and pivoted to 125 the base; means for moving the arms to cause the inking roller to traverse the selected die, and means for sliding the rotor to bring the selected die into contact with the slip to be printed.

7. A printing device including a base carrying roller guides; printing dies; a rotor holding the dies, adapted by rotation to position a selected die and slidable in the base; a roller for inking the dies mounted in the guides, and common means for moving the roller in the guides and for moving the rotor to bring the selected die into contact with the slip to be printed.
- 10 8. A printing device including a base, roller guides carried thereby; printing dies; a rotor holding the dies and slidable in the base; an inking roller mounted in the guides; pivots in the base, arms pivotally connected therewith and with the rollers; cranks freely mounted upon the pivots; coiled springs connecting the cranks and the pivots; presser arms pivoted in the base and adapted to slide the rotor to bring a selected die into contact with the slip to be printed; a lever adapted to actuate the presser arms, and links connecting the presser arms and the cranks whereby initial movement of the lever will actuate the inking roller and further movement will move the rotor to printing position.
- 15 9. A printing device including a base, roller guides carried thereby; printing dies; a rotor holding the dies and slidable in the base; an inking roller mounted in the guides; pivots in the base; arms pivotally connected therewith and with the rollers; cranks freely mounted upon the pivots; coiled springs connecting the cranks and the pivots; presser arms pivoted in the base and adapted to slide the rotor to bring a selected die into contact with the slip to be printed; a lever adapted to actuate the presser arms; links connecting the presser arms and the cranks whereby initial movement of the lever will actuate the inking roller and further movement will move the rotor to printing position.
- 20 10. A printing device including a base; pairs of vertical guides and roller guides carried by the base; printing dies; blocks slidable in the vertical guides; a rotor mounted in the blocks and carrying the dies; a shaft mounted in the base; presser arms, fixed to the shaft, adapted to engage the blocks and move the rotor downwardly; a lever fixed to the shaft and adapted to actuate the presser arms; an inking roller mounted in the roller guides; pivots in the base; arms pivotally connected therewith and with the rollers; cranks freely mounted upon the pivots; coiled springs connecting the cranks and the pivots; links connecting the presser arms and the cranks whereby initial movement of the lever will actuate the inking roller and then move the rotor to printing position, and means for returning the inking roller and the rotor to their idle positions.
- 25 11. In testimony whereof we have signed our names to this specification in the presence of two subscribing witnesses.
